(57) **CLAIM**

The ornamental design for a loop handle for a cooking vessel, as shown and described.

DESCRIPTION

FIG. 1 is a top perspective view of the “loop handle for a cooking vessel”, showing my new design;

FIG. 2 is a top plan view thereof;

FIG. 3 is a back elevation view thereof;

FIG. 4 is a side elevation view thereof;

FIG. 5 is a bottom plan view thereof;

FIG. 6 is a front elevation view thereof; and,

FIG. 7 is a bottom perspective view thereof.

The circular rivet holes in the flange portion of handle, visible at least partially in FIGS. 1, 3, 4, 6 and 7, are functional elements and are not intended to be limiting the scope of the ornamental design, forming no part thereof as claimed.

The broken lines in FIGS. 1, 3, 4, 6 and 7 form no part of the claimed design.
